US0D1018001S

(12) United States Design Patent (10) Patent No.: US D1,018,001 S
(45) Date of Patent: * Mar. 19, 2024

(54) SHOE

(71) Applicant: NIKE, Inc., Beaverton, OR (US)

(72) Inventor: Shawn G. Carboy, Portland, OR (US)

(73) Assignee: NIKE, Inc., Beaverton, OR (US)

() Term: 15 Years

(21) Appl. No.: 29/898,523

(22) Filed: Jul. 28, 2023

(51) LOC (14) Cl. 02-04

(52) U.S. Cl.

USPC D2/953; D2/951

(58) Field of Classification Search

Primary Examiner — T Chase Nelson

(74) Attorney, Agent, or Firm — Banner & Witcoff, Ltd.

(57) CLAIM

The ornamental design for a shoe, as shown and described.

DESCRIPTION

FIG. 1 is a bottom view of a shoe showing my new design;
FIG. 2 is a bottom rear perspective view thereof;
FIG. 3 is a bottom front perspective view thereof; and,
FIG. 4 is a rear view thereof.
The broken lines and unshaded areas depicting the remainder of the shoe form no part of the claimed design.

1 Claim, 4 Drawing Sheets
